UNITED STATES PATENT OFFICE.

CHARLES LA DOW, OF ALBANY, NEW YORK.

DESIGN FOR A PLOWSHARE.

SPECIFICATION forming part of Design No. 30,848, dated May 23, 1899:

Application filed January 12, 1899. Serial No. 701,997. Term of patent 14 years.

To all whom it may concern:

Be it known that I, CHARLES LA Dow, a citizen of the United States of America, and a resident of the city of Albany, in the county of Albany and State of New York, have invented and produced a certain new and original Design for Plowshares, of which the following is a specification.

Figure 1 is a plan. Fig. 2 is a section along the lines X X on Fig. 1. Fig. 3 is a top plan view. Fig. 4 is a section along the lines Y Y on Fig. 1.

Similar letters refer to similar parts throughout the several views.

My plowshare is provided with a forward downwardly-projecting point A, with a flange extending from the upward forward portion of the plowshare backward and partially over the main portion B of the plowshare. Along the lower edge a of the share I ornament the share by making it a bright smooth surface, contrasting with the dark rough surface of the

main portion B of the share. I also arrange along the forward edge a similar bright smooth surface a', and near the point A the smooth 25 bright surfaces a and a' are separated by the darker roughened portion B.

The leading or material feature of my design thus consists of a plowshare having a downwardly-extending point with a forward 30 portion provided with an overlapping flange ornamented with a ribbon-like bright surface along the lower and forward edges of the share.

What I claim as new, and desire to secure 35 by Letters Patent, is—

The design for a plowshare as herein shown and described.

Signed by me, at Albany, New York, this 10th day of January, 1899.

CHARLES LA DOW.
